UNITED STATES PATENT OFFICE

2,538,211

NOZZLE

Elmer W. Prout, La Canada, Calif., assignor to
 Akron Brass Mfg. Company, Inc., Wooster,
 Ohio, a corporation of Ohio

Application March 16, 1948, Serial No. 15,160

2 Claims. (Cl. 299—141)

1

This invention relates broadly to nozzles, and, more specifically, to improvements in nozzles of the type employed in fire-fighting equipment.

Modern fire-fighting technique relies on a special nozzle known as a fog nozzle to extinguish fires, especially those of oil and gasoline origin. In some cases, however, the fire is best controlled and put out by the old standard technique of playing a straight stream of water on the conflagration, which is based on the ram head principle.

Fires are generally complex in nature, requiring more than one type of stream to be used in abating them. Thus, it is an object of this invention to provide a combination nozzle which will deliver a straight stream of water or a fog spray at the instantaneous control of the operator.

It is a further object of this invention to provide a combination straight stream and fog nozzle with an improved valve seal system so that a complete switch from fog to straight stream, and vice versa, may be made instantaneously and without any leakage, thus giving the greatest possible efficiency to the type of stream employed by the operator.

Another object of the invention is to provide a nozzle which is constructed to direct the flow of water through a passageway that is designed to produce a columnar stream, or through a second passageway that is designed to produce a finely divided spray or fog.

Another object of the invention is to provide a valve that will effectively seal either or both of the passageways in the nozzle when the valve is adjusted to effect the closure thereof.

Another object of the invention is to provide a nozzle which is designed to facilitate the ready renewal of the wear parts and water delivery tips.

Further objects of the invention reside in the provision of a nozzle that is light in weight, sturdy of structure, economic of manufacture, and adapted for manipulation with ease and dispatch.

Other objects more or less ancillary to the foregoing, and the manner in which all the various objects are realized, will appear in the following description, which, considered in connection with the accompanying drawings, sets forth the preferred embodiment of the invention.

Referring to the drawings:

Fig. 1 is a side elevational view of the improved nozzle;

Fig. 2 is a longitudinal sectional view thereof;

Fig. 3 is a similar section illustrating the valve in an actuated position;

2

Fig. 4 is a transverse sectional view, the section being taken on a plane indicated by the line 4—4 in Fig. 3;

Fig. 5 is a longitudinal sectional view of a modified form of the nozzle illustrated in Figs. 1 to 4;

Fig. 6 is a similar sectional view thereof shown in an actuated position; and

Fig. 7 is a similar sectional view shown in a further actuated position.

Referring first to Fig. 2, the nozzle comprises generally a housing 10 having a bore 11 in the central portion thereof, a pair of passageways 12 and 13, parallel therewith, and terminating in bosses 14 and 15 in the outer end of the housing, nozzle tips 16 and 17 threaded thereon and a valve plunger 18 mounted for axial translation within the bore 11.

In detail, the valve plunger comprises a cylindrical body 19 machined for snug sliding engagement within the bore 11 and formed with a helical groove 20 in the inner end thereof for the reception of a roller 21 (Fig. 4) supported on a screw 22 mounted in the housing 10. The outer end of the plunger is bored to define a channel C constituting the inlet for the nozzle, and the throat 23 thereof is threaded and counter-bored for the reception of a hose coupling and gasket 24. The free end of the plunger is diametrically enlarged and provided with lugs 25 to accommodate rotative adjustments of the housing relative to the plunger. The inner end of the wall defining the channel C is cross-drilled to provide a plurality of ports 26 which are disposed for registration with an opening leading to the passageway 13 (Fig. 3) when the valve is adjusted to bring the roller 21 into engagement with the inner end of the groove 20. The ports 26 are closed by the wall defining the bore 11 when the valve is adjusted to bring the roller into abutting engagement with the outer end of the groove. The housing is provided with indicia (the word "Fog" as indicated in Fig. 1) to facilitate registration of the ports with the opening to the passageway 12 when the valve is adjusted to bring such marking into alignment with an arrow 27 on the enlarged end of the valve plunger 18. The bore 11 is formed with a groove 28 intermediate the openings to the passageways 12 and 13 for the reception of a soft rubber torus or so-called O-ring 29, and similar grooves 30 and 31 for like sealing elements are provided adjacent the opposed sides of the openings. A fourth groove 32 having an O-ring therein is provided in the bore in spaced relation with the inner edge of the groove 30. The web defining the

50

end wall 33 of the bore 11 is drilled to provide a vent 34 for the escapement of air entrapped between the end wall 33 and the end of the plunger.

The fog nozzle comprises a thimble 35 tapped for engagement with the threaded boss 14 and counter-bored for the reception of a gasket 36. The outer face of the end wall of the thimble is formed with a conical recess 37 having minute openings 38 therein which are drilled in normal relation to the inclined wall and arranged in opposition to each other so that the streams emitted therethrough will merge in impinged relation and form a finely divided spray. The inner face of the end wall of the thimble is of complementary configuration and further formed with a circumambient wall 39 having trans-axial holes 40 therein which are disposed in radial alignment and normal relation to openings 41 in the end wall of the thimble. As in the former case, the streams emitted through the holes 40 will impinge the contiguous streams from the openings 41 and produce a fog. The recess in the body of the thimble 35 is provided with a cylindrical screen 42 closed at its outer end and seated in its assembled relation with the open end 43 thereof upon a ledge 44 adjacent the throat of the passageway 12.

The second nozzle tip 45 is tapped for threaded engagement with the threaded boss 15 and counter-bored to support a gasket 46. The body of the tip is bored throughout its length, preferably with a tapered passageway which merges with an outer cylindrical bore 47.

Although the valve plunger is illustrated and described herein as being formed with a single row of ports 26, it will be understood that a greater number thereof may be used and that the invention contemplates such modification. For example, the plunger 50 may, if desired, be formed with a group of passageway means such as additional rows of ports 56 and 57 (Fig. 7) disposed for registration with the openings to the passageways 12 and 13 so that a straight or columnar stream of water and a fog may be delivered simultaneously by the nozzle. The single row of ports 58 is spaced from the passageway means 56 and 57 by a distance greater than the axial terminal spacing of said body canals 12 and 13 so that the water may be delivered to the passageway 12 (Fig. 5) while the other ports are blocked, or delivered to the passageway 13 (Fig. 6) when the ports 56 and 57 are closed.

The invention also comprehends the addition of a greater number of passageways similar to the conduits 12 and 13 and complementary rows of valve ports therefor, so that one or more straight streams, or one or more fog jets, may be simultaneously operated in any desired combination.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. A nozzle assembly comprising a body having an axial bore extending from one end thereof, a pair of bosses extending from the other end of the body, canals in said bosses and body communicating at their inner ends with axially spaced ports leading to said bore, nozzle tips

mounted on said bosses, a sleeve valve in said bore, said sleeve valve having first passageway means of an axial extent less than the axial spacing of said body ports and second passageway means of an axial extent substantially equal to the axial spacing of said body ports, said first and second passageway means being axially spaced by a distance greater than the axial spacing of said body ports, and helical cam means formed on said sleeve valve and body so that relative rotation thereof axially and successively advances said body relative to said sleeve, from a terminal position wherein said first passageway means is aligned with one of said body ports, to an intermediate position wherein said first passageway means is aligned with the other of said body ports, and to a second terminal position wherein said second passageway means is aligned with both of said body ports.

2. A nozzle assembly comprising a body having an axial bore extending from one end thereof, a pair of bosses extending from the other end of the body, canals in said bosses and body communicating at their inner ends with axially spaced ports leading to said bore, nozzle tips mounted on said bosses, a valve plug axially slideable in said bore, said valve plug having generally axial conduit means formed therein and arranged for communication with a source of fluid under pressure, said valve plug having first passageway means leading from said conduit means to the periphery of said plug, the axial extent of said first passageway means at the plug surface being less than the axial spacing of said body ports, said valve plug having second passageway means leading from said conduit means to the periphery of said valve plug, the axial extent of said second passageway means at the plug periphery being substantially equal to the axial spacing of said body ports, said first and second passageway means being axially spaced along the plug periphery by a distance greater than the axial spacing of said body ports, and means to cause relative axial motion of said valve plug and body from a terminal position wherein said first passageway means and one of said body ports are aligned, to an intermediate position wherein said first passageway means and the other of said body ports are aligned, and to a second terminal position wherein said second passageway means and both of said body ports are aligned.
